(57) **CLAIM**

I claim the ornamental design for an emergency light, as shown and described.

DESCRIPTION

FIG. 1 is a left perspective view of the emergency light;

FIG. 2 is a top plan view thereof;

FIG. 3 is a bottom plan view thereof;

FIG. 4 is a left side view thereof, with the right side view being a mirror image;

FIG. 5 is a rear view thereof; and,

FIG. 6 is a front view thereof.
